The ornamental design of an anesthesiology machine, as shown and described.

DESCRIPTION

FIG. 1 is a front perspective view of an anesthesiology machine showing my new design.

FIG. 2 is a top front perspective view of the anesthesiology machine shown in FIG. 1.

FIG. 3 is a top plan view of the anesthesiology machine shown in FIG. 1.

FIG. 4 is a front plan view of the anesthesiology machine shown in FIG. 1; and,

FIG. 5 is a side plan view of the anesthesiology machine shown in FIG. 1.

The solid black shading represents the color black.

The broken lines are included for the purpose of illustrating boundaries of the claimed design that enclose unclaimed portions of the anesthesiology machine, and form no part of the claimed design.
